Des. 178,908
Patented Oct. 2, 1956

178,908

CHILD'S RIDING DEVICE

Charles E. Vasaly, Kensington, Md.

Application November 5, 1954, Serial No. 32,968

Term of patent 7 years

(Cl. D34—15)

The single figure is a perspective view of a child's riding device showing my new design.

I claim:

The ornamental design for a child's riding device, as shown.
